ELECTROMAGNETIC DEVICE.

1,071,905.

Specification of Letters Patent. Patented Sept. 2, 1913.

Application filed October 26, 1911. Serial No. 656,938.

To all whom it may concern:

Be it known that we, MAURICE F. GEER and RICHARD C. LEAKE, citizens of the United States, and residents of the city of 5 Rochester, in the county of Monroe and State of New York, have invented a new and useful Electromagnetic Device, of which the following is a specification.

This invention relates to an electro-magnetic device.

The primary object of this invention is to increase the efficiency of an electro-magnetic device.

A further object of this invention is to decrease the friction produced by the movement of a movable member of an electro-magnetic device.

A further object of this invention is to produce a support for the movable element 20 of an electro-magnetic device which will offer no resistance to the movement of the movable element.

In electro-magnetic devices as heretofore constructed in which a movable armature has been employed, it has been customary to mount the armature upon a pivot pin which was cone shaped at both ends and which was held in place by two screws passing through 25 fixed objects and having a conical cavity in their ends. When such a construction is employed, it is necessary to have the pivot pin and the supporting screws made of dissimilar metals in order to reduce friction to a minimum and this has resulted in making 30 the screws of brass and the pivot pin of steel as being the most readily available materials.

Even if the screws are not made of brass they must be made of a non-magnetic material in case the fixed object through which 40 they pass is connected in any way with the magnetic circuit of the electro-magnetic device for if the screws are connected with the magnetic material of the electro-magnetic device they would, by reason of their magnetic attraction for the steel pivot pin prevent the armature from moving freely. This on first thought may appear to be far fetched, but in actual practical operation, it 45 has been found to be of serious moment. It is also necessary when such a construction is employed in order to prevent wabbling of the armature to bind the pivot pin quite closely between the screws thus introducing 50

a considerable friction, and it has also been 55 found that on account of the expansion and contraction caused by difference of temperature that it is an extremely difficult matter to so adjust the tightness of the screws upon the steel pivot pin that it will not be bound 60 so tightly that it will not move at all in extremely hot weather in case the adjustment happens to be made in cold weather.

An electro-magnetic device employing a movable armature, in order to operate at the 65 greatest efficiency should have the least possible air gap in the magnetic circuit but with the construction above mentioned, due to the fact that the pivot pin on which the armature is supported is held in place by brass 70 screws, an undesirable gap in the magnetic circuit is introduced which, by applicants' method of construction is avoided, as will be hereafter pointed out.

In describing the invention in detail, reference will be had to the accompanying drawings, on which like characters of reference refer to like parts, and in which applicants have shown a preferred form of mechanism embodying the principle of their invention, and in which:

Figure 1 is a front elevation of an electro-magnetic device. Fig. 2, is a side elevation of an electro-magnetic device. Fig. 3, is an enlarged detail cross sectional view upon the 85 line A—B of Fig. 1. Figs. 4, 5 and 6 are detail views of a knife edge bearing employed in the electro-magnetic device.

Applicants have embodied the principle of their invention in an electro-magnetic device commonly known as an electric bell, which is shown in front elevation by Fig. 1, in which, 1 designates a mounting plate, which as best shown by Fig. 2, has outstanding lugs 2, formed integral therewith and 90 through which pass screws 3, which pass through the bell mounting strip 4, and into the iron yoke 5, supporting the bell mounting strip 4 and the yoke 5 firmly in place. The bell mounting strip 4 has at either end 100 the gongs 5 and 6 attached thereto by means of screws 7. The iron yoke 5 has slots 8 and 9 near either end which extend into screw threaded holes 10 in the yoke; 11 and 12 designate iron cores which are screw 105 threaded on their upper end and which are screwed into the threaded holes in the yoke 5 and which are clamped in adjusted posi-

tion by means of the screws 13 which act to narrow the slots 8 and 9 and so bind the cores in place; 14 designates a screw which passes through the yoke 5 and is screwed into the iron or steel member 15, which bears upon its lower end the knife edge bearing 16, shown in detail by Figs. 4, 5 and 6, which is attached thereto by means of the screw 17, which screw also supports the 10 angularly bent member 18; 19 designates an armature which has a V shaped groove 20 formed therein and which bears against the knife edge bearing 16, and has a member 21 screwed into it and therefore adjustable, 15 which member has a cone shaped cavity therein, which as best shown in Fig. 3, terminates on a line with the edge of the knife edge bearing 16; 22 designates a pin, cone shaped at its upper end and resting in the 20 cone shaped cavity in the member 21 and headed at its lower end and resting upon the resilient member 23, which resilient member is supported at either end by means of screws 24 and 25, which are screw threaded 25 into the member 18, there being a lock nut on each screw to retain it in adjusted position. It will be noted that the member 23 is bowed slightly as it exerts an upward tension upon the pin 22, and that the tension exerted by the member 23 upon the pin 22 can be varied by screwing in or out the screws 24 and 25.

Each end of the member 18 has an insulating sleeve 34 passed therethrough which 35 has a hole passing therethrough which is screw threaded, and into which is threaded the screws 27 and 28, and upon each screw are nuts 29 and 30 which hold the terminals of the wires 31 and 32 in contact with the 40 screws 27 and 28 and act as lock nuts for screws 27 and 28. Two flat springs 33 and 34 lie directly over the ends of the screws 27 and 28 and are riveted by rivets 35 and 36 respectively to the armature 19, one of 45 the springs 34, as shown in Fig. 1, normally resting against the end of screw 28, it is practically immaterial however whether one or both of the springs rests against the screws.

50 The member 21 which is screw threaded into the armature 19 has a projecting end 37 which is drilled to receive the rod 38, which bears upon its upper end the hammer 39 adapted to strike the gongs 5 and 6 as 55 it is moved back and forth by the oscillation of the armature 19. The cores 11 and 12 have wound upon them the wires 32 and 31 respectively which are joined together at the upper end by being placed under the 60 binding screw 40, and wire 41 leads from the binding screw 40 to the terminal 42 to which the wire from the source of current is led to the electro-magnetic device; the other terminal from the source being connected to the binding post 43, and the bind-

ing post 43 being connected by the wire 44 to the gong support 4 thus grounding it upon the frame of the electro-magnetic device.

The operation of the device is as follows: Current entering at the binding post 42 passes through wire 41 to the binding post 40 and thence by wire 32 to the screw 28, thence to the spring 34 and through the metal frame to the gong support 4 and then by wire 44 to binding post 43 and to the other terminal of the source of current. Current flowing in the above traced path causes the right hand end of the armature 19, as viewed in Fig. 1, to be raised, thereby 70 causing the hammer 39 to strike against the left hand gong 6, but the upward movement of the armature causes the spring 34 to break contact with screw 28 and at the same time the spring 33 is brought into contact with screw 27, thus completing a circuit from the binding post 40 through wire 31, screw 27, spring 33 and metal frame to the binding post 43, so that the left hand end of armature 19 is then attracted by the core 12 causing the hammer 39 to strike the right hand gong 5, this of course causes spring 34 to again make contact with screw 28 and the actions are then repeated as long as current is fed to the device.

It is to be noticed that the wires 32 and 31 are so wound upon the cores 12 and 11, that when current flows through them the lower ends of the cores will always have the same polarity which we will call south, as 100 indicated on Fig. 1. It is also to be observed that the armature 19 is in direct magnetic contact with the knife edge bearing 16, which is formed of magnetic material and that the knife edge bearing 16 is in direct 105 magnetic contact with the body 15 which is also made of magnetic material and that the body 15 is in direct magnetic contact with the yoke 5, which is of magnetic material and that the yoke 5 as is customary is in 110 direct magnetic contact with the cores 11 and 12, so that when current flows through either coil of wire 31 or 32 a magnetic flux is generated in cores 12 or 11 which passes down through member 15, knife edge bearing 16 and armature 19 to the lower end of the poles so that the only air gap which occurs in the magnetic circuit is that which occurs between the ends of the armature 19 and the ends of the cores 11 and 12. Such 115 a construction produces an extremely efficient electro-magnetic device, for a complete path for the magnetic flux through magnetic material is formed, except at the one place where the flux must pass through 120 air in order to enable the movement of the armature to take place and as the same conditions hold as regards the magnetic flux generated by both coils the device is equally 125 efficient on both sides.

As the armature 19 oscillates upon a knife edge, it is without friction, consequently, the armature has the freest possible movement both when being drawn toward the poles and when returning to normal position, furthermore the method of support herein employed allows the armature to move from its normal position without in any way increasing the tension of the member supporting the armature, for the member 22 terminates exactly in line with the edge of the knife edge bearing so that whatever oscillation takes place no movement of the part or point of the armature against which rests the pin 22 takes place. It is also readily seen that the member 23 can be so adjusted by movement of the screws 24 and 25, as to exert any desired pressure upon the member 22.

Although applicants have herein shown and described their invention as embodied in an electric bell of the non-polarized direct current type, it is to be distinctly understood that applicants' invention in its broadest aspect, may be embodied in various electro-magnetic devices as, for instance, the ordinary alternating current electric bell, in which case springs 33 and 34 would be dispensed with and the two coils upon the two cores would be in series and the source of alternating current would be connected directly to the free ends of the coils, thus forming a construction which is well understood and known to those skilled in the art.

In such case, however, it would be necessary to polarize the armature 19, which would be in applicants' form of invention herein shown an extremely simple matter, for the member 15 would be, in such case, formed as a permanent magnet having its lower end formed as, say, a north pole, and the alternate flow of current through the coils would alternately cause the lower ends of the cores 11 and 12 to assume an opposite polarity to that of the lower end of member 15 thus causing an oscillation of the armature 19 in a manner well understood. It is also to be observed that in such case the magnetic flux through member 15 would always be in the same direction, thus tending to build up the permanent magnetism, rather than to destroy it. It is also to be understood that applicants' invention is applicable to a relay device, that is to say, a contact maker could be attached to the rod 38 so as to complete or break circuits as desired according to its position, in which case, of course, the contact springs 33 and 34 would be dispensed with and the two coils upon the cores would be in series with their free ends, connected directly with the external circuit, containing a device for reversing the current flow as is well understood.

Having thus described the principle of our invention and illustrated a preferred

form embodying that principle, what we claim as new and desire to secure by Letters Patent, is:

1. In an electro-magnetic device, a movable armature, a knife edge bearing for the armature, a pin adapted for holding the armature against the knife edge bearing, an adjustable member between the pin and the armature, said pin terminating substantially on a line with the knife edge of the bearing, and means to support the pin. 70

2. In an electro-magnetic device, a movable armature, a knife edge bearing for the armature, a pin adapted for holding the armature against the knife edge bearing, an adjustable member between the pin and the armature, said pin terminating substantially on a line with the knife edge of the bearing, and adjustable means to support the pin. 80

3. In an electro-magnetic device, a movable armature of magnetic material, a knife edge bearing of magnetic material against which the armature is in direct magnetic contact and on which the armature may oscillate, a pointed pin adapted to support the armature in contact with the knife edge, a member between the pin and the armature formed with a conical cavity in which the pin rests, means to support the pointed pin, a body of magnetic material in magnetic contact with said knife edge bearing at one end, cores with which said magnetic body are in magnetic contact at the other end, coils about said cores adapted to convey current, and an arm moved in unison with said armature. 95

4. In an electro-magnetic device, a movable armature of magnetic material, a knife edge bearing of magnetic material against which the armature is in direct magnetic contact and on which the armature may oscillate, a fixed point to support the armature in contact with the knife edge, an adjustable member between the point and the armature, a body of magnetic material in magnetic contact with said knife edge bearing at one end, a core with which said magnetic body is in magnetic contact at the other end, a coil about said core adapted to convey current and thus attract said armature to said core, and an arm moved in unison with said armature. 105

5. In an electro-magnetic device, a movable armature, a knife edge bearing for the armature, said armature formed with a cone shaped cavity therein having the apex of the cavity on a line with the knife edge, a pin bearing on the apex of the cavity and means to support the pin. 110

6. In an electro-magnetic device, a movable armature, a knife edge bearing for the armature, a pointed pin adapted for holding the armature against the knife edge bearing, said pin terminating substantially on a line with the knife edge of the bearing, 125

an adjustable member between the pin and the armature formed with a conical cavity in which the pin rests, and means to support the pin.

- 5 7. In an electro-magnetic device, a permanent magnet, a member of magnetic material formed with a knife edge attached to said magnet, both mechanically and magnetically, an armature bearing on said knife edge and having an adjustable member attached thereto having a cone shaped cavity formed therein, said member formed with a knife edge and also formed with a hole therethrough, an oscillatable member in said hole attached to said armature, means to utilize said last named member, a pin resting in said cone shaped cavity with its extremity in line with the knife edge, and means to support said pin.
- 10 8. In an electro-magnetic device, a yoke of magnetic material, magnetic rods, means for adjustably connecting the rods and yoke and holding the rods in adjusted position, a member made of magnetic material fastened

to the yoke between the rods, a knife edge 25 bearing of magnetic material attached magnetically to the last named member, an armature of magnetic material oscillatable on the knife edge and having extremities in operative relation with said magnetic rods, 30 said armature having contact plates thereon, contact points in operative relation with said plates, a member insulatingly supporting said points, and also including means to support said armature, conducting coils having two terminals surrounding said magnetic rods, one terminal of each coil being connected to a separate contact point, the other terminals of the coils being connected one to the other forming a line terminal, said 35 armature being connected to another line terminal, means for utilizing motion of the armature.
